LESLIE R. SAUNDERS, OF LOS ANGELES, CALIFORNIA.

CIRCUIT-CLOSING DEVICE.

973,818.

Specification of Letters Patent. Patented Oct. 25, 1910.

Application filed February 21, 1910. Serial No. 545,187.

To all whom it may concern:

Be it known that I, LESLIE R. SAUNDERS, a citizen of the United States, and a resident of Los Angeles, in the county of Los Angeles and State of California, have invented a new and Improved Circuit-Closing Device, of which the following is a specification.

This improvement relates to means for intermittently closing and opening electric circuits, especially the primary circuits of explosion-engine sparking devices, and the object of this invention is to provide a motor-driven mechanism which shall regularly close an electric circuit and again open the same, the rate of these operations depending upon the speed of the motor, but the periods during which the circuit is closed being extremely short and entirely independent of the speed of the motor.

In the accompanying drawings, Figure 1 is a plan of this improved circuit-closing device with the cover and the holding-down spring removed. Fig. 2 is a similar view with the parts in a slightly different position. Fig. 3 is a cross section on the line 3—3 of Fig. 1. Figs. 4, 5 and 6 are details.

Similar reference characters refer to like parts throughout the several views.

The case of this circuit closing device may be of any desired configuration, that shown being in the form of a hub 1 joined to a shell 2. In the hub is mounted a driver 3 which may be connected to the motor in any desired manner. While bearing rings 4 and balls 5 of a ball-bearing are shown, this refinement is not necessary to the operation of this device, although desirable.

Projecting upward from the driver 3 is a central pin or journal 6 on which is mounted a collar 7 having any desired number of teeth 8, four being shown. This collar has a notch 9 on its lower side into which the tooth 10 on the driver projects. This tooth 10 is beveled on its rear side, so that when the driver runs backward, that is, to the left, the only effect will be that the collar 7 will be lifted up. A post 12, projecting from the bottom 13 of the case, supports a flat spring 14, which has an opening at its free end so it may be held from swinging by the pin 6, which extends through this opening. This spring will always press down on the collar 7. By these means, the tooth 10 will

always be caused to engage in the notch 9 when the driver turns to the right. The collar 7 and its teeth 8 together are the immediate means for causing the closing of the circuit and are called the actuator. The circuit may connect directly to the case on one side as by the wire 41, while the other side may connect to the insulated abutment 17 through the screw 18, the wire 19 passing out through any desired opening, such as 20 in the bottom 13. This abutment 17 carries a contact element, preferably in the form of a screw 22. Any other desired electrical connection can be made with this contact element.

Movably mounted in the case, preferably on a pivot screw 25, is a lever 26 having its free end curved to form a hook to engage the free end of the spring 27 secured to this lever near its pivot. A contact element 30 of platinum or other suitable metal may be mounted on this spring. The lever is held away from the contact 22 by any desirable means, a light coil-spring 29 being preferred. A cam-shoulder 28 on this lever is adapted to be engaged by the teeth 8 of the actuator to swing the lever and spring 27 toward the abutment and force the contact 28 against the screw 22. A pin 31 prevents the spring 29 from swinging the lever in too far.

Movably mounted in the case, preferably pivoted on a screw-pin 33, is the accelerator 34 which has a heel 35 normally bearing against the pin 36, and normally held in the position shown in Fig. 1 by any desired resilient device such as the spring 37 carried by the post 12. On this accelerator is a cam-shoulder 39 adapted to be engaged by one tooth of the actuator, while its outer end is curved inwardly to form a finger 40 to engage another tooth.

The operation of this mechanism is as follows. The tooth 10 will turn the actuator at the speed of the driver 3 and a tooth 8^a will engage the cam-shoulder 39, pushing back the accelerator against the tension of its spring 37, until the parts are in the position shown in Fig. 1. As soon as this tooth 8^a has passed the cam-shoulder 39 the spring 37 will snap the accelerator inward to the position shown in Fig. 2, and the finger 40 will strike the second tooth 8^b and carry the actuator around from the position shown in Fig. 1, to that in Fig. 2 the tooth

8^e passing the cam-shoulder 28 on the lever. During the instant this tooth passes this shoulder, the circuit will be closed. Because of the length of the notch 9, the accelerator can revolve the actuator in advance of its driving tooth 10. It will therefore be clearly seen that the length of time the circuit remains closed will always be extremely short, and will generally be the 10 same, being the time a tooth 8 is passing the shoulder 28 on the lever. And as this motion is under the control of the accelerator and its spring 37, the period will depend upon the stiffness of the spring, and will 15 be absolutely independent of the speed of the driver, until the speed of the driver is sufficiently rapid to move the actuator at the same or greater speed than may be done by the accelerator and its spring. Any 20 desired cover 42 may be employed, that shown being held in position by screws 43. In case the driver is turned in the reverse direction, a tooth 8 will immediately engage the shoulder 28 on the lever 26. The tooth 10 25 will move until it reaches the rear end of the notch 9 when its inclined rear side will engage the incline 44 (Fig. 5) lifting the actuator against the spring 14. The driver can thus revolve without closing the circuit, 30 no tooth 8 passing the shoulder 28 to swing out the lever 26 and the contact 30. As has been explained, the teeth 8 engage and pass the shoulder 28 while the actuator is being driven by the accelerator, and the accelerator 35 drives the proper tooth entirely past the shoulder 28. It is therefore impossible for this device to stop in closed circuit position.

The extreme simplicity of the construction and the accessibility of the various parts 40 makes this circuit closing device especially adapted for use by the general public.

Many changes in the details of construction may be made by those skilled in the art without departing from the spirit of my 45 invention.

Having now explained my improvements, what I claim as my invention and desire to secure by Letters Patent is:—

1. In a circuit closing device, the combination of a plurality of contact elements 50 movable relatively to each other, a revoluble driver, a collar adapted to cause the contact points to engage, said collar revoluble with said driver, and an accelerator, a spring 55 to drive the same, to revolve said collar during the time it forces the contact points to engage.

2. In a circuit closing device, the combination of a contact-element in an electric circuit 60 adapted to be moved to close said circuit, an actuator to periodically move said contact-element to circuit closing position, means to normally move said actuator at constant speed, an accelerator adapted to be positioned by the actuator, and a spring to

return the accelerator and thereby move the actuator at increased speed while closing the circuit.

3. In a circuit closing device, the combination of a contact-element in an electric circuit 70 adapted to be moved to close said circuit, an actuator revoluble to periodically move said contact-element to circuit closing position, means to normally drive the actuator at a constant speed, an accelerator and 75 spring to tension the same, said accelerator positioned to normally engage the actuator and be forced back by the same against the tension of the spring and then released to engage the actuator at increased speed while 80 it causes the closing of the circuit.

4. In a circuit closing device, the combination of a contact-element in an electric circuit 85 adapted to be moved to close said circuit, a motor-driven revoluble actuator to periodically move said contact-element to circuit closing position, a driver to support and normally revolve said actuator at constant speed, and a reciprocating spring-driven accelerator for turning said actuator at increased speed while it causes the 90 closing of the circuit.

5. In a circuit closing device, the combination of a contact-element in an electric circuit 95 adapted to be moved to close said circuit, an accelerator, a spring to drive the same, and an actuator to periodically move said contact-element to circuit closing position under an impulse from the accelerator, and a driver for moving said actuator between the impulses from the accelerator. 100

6. In a circuit closing device, the combination of a contact-element in an electric circuit 105 adapted to be moved to close said circuit, a reciprocating spring-driven accelerator, a revolving actuator to periodically move said contact-element to circuit closing position under an impulse from the accelerator, and a revoluble driver supporting said actuator and revolving the same between the impulses from the accelerator. 110

7. In a circuit closing device, the combination of a stationary and a movable contact element, a revoluble driver, a toothed actuator mounted thereon and intermittently revolved thereby, an accelerator pivoted adjacent said actuator and adapted to be swung outward thereby, and a spring engaging said accelerator to return the same to engage the actuator to revolve the same 115 between the movements imparted by the driver, said actuator engaging the movable contact element under the impulse of the accelerator to cause the closing of the circuit. 120

8. In a circuit closing device, the combination of a plurality of contacts for closing the circuit, a revoluble driver, a toothed actuator for causing the contacts to engage, an accelerator adapted to be moved to operative 125 130

position by said actuator, a spring to operate said accelerator to engage the toothed actuator to turn the same and thereby cause the closing of the circuit, and independent 5 means to immediately open said circuit.

9. In a circuit closing device, the combination of a contact-element movable to close an electric circuit, an actuator to periodically move the contact-element to circuit closing position, means to normally revolve said actuator at constant speed in one direction, 10 means to prevent said actuator from turning

in the opposite direction, and an accelerator adapted to be positioned by the actuator and spring driven for moving said actuator 15 at increased speed while it causes the closing of the circuit.

In testimony whereof I have signed this specification in the presence of two subscribing witnesses.

LESLIE R. SAUNDERS.
